UNITED STATES PATENT OFFICE.

GEORGE F. SWORTFIGER, OF EAST ORANGE, NEW JERSEY.

THIMBLE FOR CABLE CONNECTIONS.

1,243,459.

Specification of Letters Patent. Patented Oct. 16, 1917.

Application filed March 21, 1916. Serial No. 85,631.

To all whom it may concern:

Be it known that I, GEORGE F. SWORTFIGER, a citizen of the United States, and resident of East Orange, in the county of 5 Essex, State of New Jersey, have invented a new and useful Improvement in Thimbles for Cable Connections, of which the following is a specification.

This invention relates to cable fastenings, 10 and particularly to the thimbles that are employed within the loop of the cable where the loop attaches to another loop or to an anchorage. Its object is to make the thimble more easily controllable; and the object is 15 attained by the means set forth in this specification and the accompanying drawings.

Figure 1 is a plan of a thimble with the improvement attached. Fig. 2 is a longitudinal section through the center of the 20 thimble. Fig. 3 is a side elevation of the thimble. Fig. 4 shows the application of this invention.

A trouble experienced in the use of the thimble shown is that in drawing the cable 25 through an anchor eye, the tendency is for the thimble to follow the cable, so that the attention of a man is required to keep the thimble in its proper place. In Fig. 4 is shown the application of my invention to 30 the thimble, which consists of the addition to the thimble of lug projections *c c*, and the illustration makes it apparent how the projections will serve to prevent improper movement of the thimble.

Fig. 1 represents a thimble with this improvement attached. The thimble comprises 35 a semicircular part with limb extensions *b*

b, the whole made of curved bar iron or steel, the concave side of the rod being upon the outside of the thimble. Projections *c c* 40 are formed upon the inner face of the thimble, one upon each side of the space to be occupied by the attached cable anchorage, the projections to be of sufficient length to prevent their slipping under the parts they 45 are intended to abut against.

As will be plain from reference to Figs. 2 and 3 these projections are not set upon the thimble, but are formed out of the body of the thimble, by punching or pressing from 50 the outside. While the thimble is supported upon a form, depressions are made by means of a punch in a press, the extended walls of the projections being shown in cross section at *e e*, Fig. 2. No particular form of ex- 55 tension is essential so long as it serves the purpose of preventing the moving of the thimble with the cable.

Having described my invention, what I claim and desire to secure by Letters Patent, 60 is—

1. A thimble for cable anchorage provided with projections upon its inner face adjacent to the part of the thimble to be occupied by the anchorage. 65

2. The combination with a cable, a thimble and an anchor eye, of projections on the inner face of the thimble to prevent the thimble turning in the anchor eye.

GEORGE F. SWORTFIGER.
